ERNEST B. FREEMAN, OF NEWTON, MASSACHUSETTS, ASSIGNOR TO B. F. STURTEVANT COMPANY, OF HYDE PARK, MASSACHUSETTS, A CORPORATION OF MASSACHUSETTS

HEAT EXCHANGE APPARATUS

Application filed August 22, 1930. Serial No. 477,030.

The present invention relates to heat exchange apparatus and more particularly to a combined economizer and air heater for heating both the feed water for the boiler and the air delivered to the furnace.

The object of the present invention is to provide a combined economizer and air heater of simple, compact and efficient construction.

With this object in view, the principal feature of the present invention comprises a plurality of double heat exchange elements, each comprising tubes arranged one within the other to form two conduits, one for water and the other for air. The elements are arranged in a flue preferably in staggered relation to be heated by the hot flue gases. Each set of air tubes is divided into a plurality of banks or rows connected with suitable collecting chambers to permit parallel flow through the tubes of each bank, and a similar arrangement may be provided to permit parallel flow of water through banks of water tubes. The invention may be constructed in either of two forms, namely, with the water tubes inside the air tubes or with the air tubes inside the water tubes. The first form of the invention is advantageous in that it permits heating of the air to a higher temperature than the water, as is ordinarily required for maximum economy. On the other hand, the second form of the invention, in which the water conduits are external to the air conduits, possesses the advantage of superior heat transmission from the hot gases to the water. In any case, both the air and water tubes are disposed across and through the entire flue to obtain maximum heat transfer with minimum loss of heat in the waste gases to the atmosphere.

Other features of the invention consist of certain novel features of construction, combinations and arrangement of parts herein-after described and particularly defined in the claims.

In the accompanying drawings illustrating the invention in its preferred forms, Fig. 1 is an end elevation partly in section of one form of the invention employing internal

water conduits and external air conduits; Fig. 2 is a section on line 2—2 of Fig. 1; Fig. 3 is an elevation partly in section of a modified form of the invention; Fig. 4 is a section on line 4—4 of Fig. 3; Fig. 5 is an elevation partly in section of another form of the invention employing internal air conduits and external water conduits; and Fig. 6 is a section on line 6—6 of Fig. 5.

The embodiment shown in Figs. 1 and 2 comprises a flue 8 through which the hot gases pass in an upward direction. A plurality of double heat exchange elements 10 are arranged horizontally in the flue. Each heat exchange element comprises an outer air tube 12 and an inner water tube 14. The ends 16 of the casing 8 comprises tube sheets for the air tubes 12, each sheet having a plurality of holes into which the ends of the air tubes are expanded. The elements are arranged in a plurality of rows, shown as six rows, each of four elements. The elements of adjacent rows are offset, as shown in Fig. 1, to stagger the tubes in the customary manner. At one end of the apparatus are an inlet collecting chamber 18 communicating with some of the air tubes and an outlet collecting chamber 20 communicating with the remainder of the air tubes. At the opposite end of the apparatus is a single collecting chamber 22 communicating with all of the air tubes. The inlet and outlet chambers are separated by a baffle 24. The chambers 18, 20 and 22 are enclosed by an insulated casing 26. Air inlet and outlet ducts 28 and 30 lead through the casing to the chambers 18 and 20 respectively. The water tubes 14 extend beyond the ends of the air tubes and into the air collecting chambers. The water tubes are connected in series for a single serpentine flow of water therethrough, by means of horizontal return bends 32 connecting adjacent tubes of the several rows, and inclined return bends 34 connecting end tubes of adjacent rows. Water inlet and outlet connections 36 and 38 are provided for the first and last tubes, respectively. The water tubes are supported on horizontal angle irons 40 disposed below the return bends.

In operation, the hot flue gases flow up-

wardly through the flue over the external surfaces of the elements 10. The air and water admitted through their respective inlets flow horizontally across the flue, and in 5 a general downward direction counter-current to the gases. By the baffle 24 the air heater is divided into two banks of tubes, each bank comprising three rows of four tubes each. Thus, the air flows from the inlet 10 chamber 18 through the upper bank of twelve air tubes in parallel into the collecting chamber 22, and thence through the lower bank of twelve air tubes in the opposite direction to the outlet chamber 20. The water courses 15 back and forth from one tube to the next in the first row, and then through the tubes of the second row in series, and so on, until it reaches the outlet. The air, because of the 20 large volume which must be passed through the apparatus, is preferably caused to flow through only two banks, whereas the water because of its relatively small volume is passed at considerable velocity through all of the tubes in series.

25 In operation, the air is heated to a high temperature by its passage through the outer conduits 12 which are heated by the flue gases. A portion of the heat extracted from the flue gases by the air is taken up by the water which 30 flows through the inner conduits 14.

35 In this form of the invention, the water tubes are immediately accessible for repair or replacement. Access may also be easily gained to any air tube by merely removing its internal water tube, an operation which is readily accomplished by disconnecting the 40 return bends at opposite ends thereof. If actual removal of an air tube is required, it may be necessary to take out a pair of the angle irons 40, and if this is done, care should be taken to block up the other water tubes of the row temporarily.

45 The embodiment of the invention shown in Figs. 3 and 4 is similar to that shown in the preceding figures, except that provision is made for dividing the water tubes into a plurality of parallel flow sections or banks. The flue 8, the double elements 10, each including an external air tube 12 and an internal water tube 14, the baffle 24 for dividing the air tubes into two banks, and the casing 26 are exactly similar to the corresponding parts 50 previously described. Each row of water tubes, however, is connected at opposite ends into water collecting chambers or headers 42, by which the water is compelled to flow in parallel through all four tubes of each row. Each header has openings into which the 55 tubes are expanded. In the outside wall of each header and opposed to the tubes are a plurality of openings which are closed by the caps 44. These openings afford access to the water tubes to permit insertion of an expanding tool to connect the tubes into the 60 headers. A water inlet connection 46 leads

65 into one header of the uppermost section and an outlet connection 48 leads from a header of the lowermost section. Headers of adjacent rows are connected by return bends 50. The headers are supported on side angle 70 irons 52.

75 It will be seen that the air tubes are divided into two banks, each consisting of three rows of tubes, through which the air flows in parallel, and the water tubes are divided into six banks, each consisting of a single row of tubes.

80 As in the previously described embodiment, access to the water tubes is simple and direct, it being only necessary to remove a cap 44 to reach any water tube. To repair an air tube, it is only necessary to remove the water headers for the corresponding row.

85 The embodiment of the invention shown in Figs. 5 and 6 is similar to that shown in the preceding figures, in that it comprises a plurality of double heat exchange elements but differs in that the air is carried by the inner conduits and the water in the annular space 90 between the tubes. This embodiment of the invention comprises the flue 60 having a plurality of rows of double heat exchange elements 62 arranged in staggered relation, as shown, in six rows of four each. Each element comprises an outer water tube 64 and an inner air tube 65. The outer or water tubes 64 are expanded into horizontal headers 66 which are attached to the end plates or tube sheets 68 of the flue. In the outside wall of each header are openings of at least as great a diameter as that of each water tube. Received in each opening is a plug 70 having a smaller concentric opening through which the 95 end of the air tube passes. The air tube is expanded into the plug 70. The air tubes thus extend through the headers into collecting chambers 72 and 74 at one end and a collecting chamber 76 at the other end. The 100 chambers 72 and 74 which form air inlet and outlet chambers, respectively, are separated by a baffle 78. Inlet and outlet ducts 80 and 82 communicate with the chambers. A water inlet pipe 84 leads into the water header of the uppermost section and an outlet tube 86 leads from the header of the lowermost section. Headers of adjacent rows are connected 105 at the ends by return bends 88.

110 As in the other embodiments of the invention, the apparatus shown in Figs. 5 and 6 provides for a division of the heat exchange elements into a number of banks with a smaller number of banks for the air tubes than for the water tubes. Each air bank comprises three rows of air tubes and each water bank comprises a single row of water 115 tubes.

120 All of the tubes of the apparatus are accessible for repair or replacement without the necessity for dismantling the entire apparatus. Thus, any air tube is immediately 130

- accessible by removing the outer casing, and any water tube is easily made accessible by first removing the corresponding air tube and then the plug 70.
- 5 Having thus described the invention, what is claimed is:
1. Heat exchange apparatus comprising a set of air tubes and a set of water tubes, the separate tubes of one set being contained within the separate tubes of the other set, a flue for hot waste gases in which the tubes are disposed, collecting chambers to divide the set of air tubes into a plurality of banks, each including a number of parallel flow tubes, and flanged detachable return bends for connecting water tubes. 75
  2. Heat exchange apparatus comprising a set of air tubes and a set of water tubes, a flue for hot waste gases in which the tubes are disposed, the separate tubes of one set being contained within the separate tubes of the other set, collecting chambers to divide the set of air tubes into a plurality of banks, each including a number of parallel flow tubes, the water tubes projecting beyond the ends of the air tubes and into the collecting chambers, connecting means for the water tubes, and means for supporting the water tubes. 80
  3. Heat exchange apparatus comprising a set of air tubes and a set of water tubes, the separate tubes of one set being contained within the separate tubes of the other set, collecting chambers to divide the set of air tubes into a plurality of banks, each including a number of parallel flow tubes, the water tubes projecting into the collecting chambers beyond the ends of the air tubes, individual return bends connecting the water tubes to cause series flow of water therethrough, and means in the collecting chambers for supporting the water tubes. 85
  4. Heat exchange apparatus comprising a plurality of double heat exchange elements, each consisting of an external air tube and an internal water tube projecting beyond the ends of the air tube, air collecting chambers at the ends of the air tubes, baffle means to divide the air tubes into a plurality of banks having provision for parallel flow of air through the tubes thereof, and individual return bends connecting the water tubes to cause series flow of water therethrough. 90
  5. Heat exchange apparatus comprising a plurality of double heat exchange elements, each consisting of an external air tube and an internal water tube projecting beyond the ends of the air tube, air collecting chambers at the ends of the air tubes, baffle means to divide the air tubes into a plurality of banks having provision for parallel flow of air through the tubes thereof, individual return bends connecting the water tubes to cause series flow of water therethrough, and means for supporting the water tubes. 95
  6. Heat exchange apparatus comprising a plurality of double heat exchange elements, each including a tube within another tube, one of which is adapted to carry feed water and the other air for combustion, the inner and outer tubes forming two separate sets, a flue for hot waste gases in which the tubes are disposed and means for dividing each set into a plurality of banks comprising a number of tubes through which the fluid flows in parallel. 100
  7. Heat exchange apparatus comprising a flue for hot waste gases, a set of air tubes and a set of water tubes, each of the separate tubes of one set being contained within a separate tube of the other set, means for dividing the air tubes into a plurality of banks of parallel flow tubes, and means for dividing the water tubes into a plurality of banks, the air banks having a greater number of tubes than the water banks. 105
  8. Heat exchange apparatus comprising a flue for hot waste gases, a plurality of water tubes and a plurality of air tubes, the separate water tubes being contained within and projecting beyond the ends of the air tubes, collecting chambers communicating with the air tubes, and headers connected with the water tubes and disposed in the collecting chambers. 110
  9. Heat exchange apparatus comprising a plurality of rows of double heat exchange elements, each consisting of an external air tube and an internal water tube projecting beyond the ends of the air tube, collecting chambers at the ends of the air tubes, a pair of headers for each row of water tubes, the headers being disposed in the collecting chambers, and connections between headers of adjacent rows. 115
  10. Heat exchange apparatus comprising a plurality of rows of double heat exchange elements, each consisting of an external air tube and an internal water tube projecting beyond the ends of the air tube, a plurality of collecting chambers to permit parallel flow of air through several rows of air tubes in parallel, a pair of headers for each row of water tubes to permit parallel water flow through the tubes of each row, and connections between headers of adjacent rows. 120
  11. Heat exchange apparatus comprising a plurality of rows of double heat exchange elements, each consisting of an external air tube and an internal water tube projecting beyond the ends of the air tube, a plurality of collecting chambers to permit parallel flow of air through several rows of air tubes in parallel, a pair of headers for each row of water tubes to permit parallel water flow through the tubes of each row, connections between headers of adjacent rows, and means for supporting the headers in the collecting chambers. 125
  12. Heat exchange apparatus comprising a 130

plurality of water tubes, a plurality of air tubes, each air tube being contained within a water tube, a flue for hot waste gases in which the tubes are disposed, a plurality of 5 headers arranged at each end of the water tubes, each communicating with a plurality of tubes, and air collecting chambers each communicating with a plurality of air tubes.

13. Heat exchange apparatus comprising a 10 set of air tubes and a set of water tubes, the separate air tubes being contained within the separate water tubes, and projecting beyond the ends of the water tubes, serially connected headers for the water tubes and collecting 15 chambers for the air tubes to form a plurality of banks of parallel flow tubes for each set.

14. Heat exchange apparatus comprising a 20 set of air tubes and a set of water tubes, the separate air tubes being contained within the separate water tubes, and projecting beyond the ends of the water tubes, headers for the water tubes and collecting chambers for the air tubes to form a plurality of banks 25 of parallel flow tubes for each set, the banks of air tubes having a greater number of tubes than the banks of water tubes.

15. Heat exchange apparatus comprising a 30 set of air tubes and a set of water tubes, separate air tubes being contained within the separate water tubes, and projecting beyond the ends thereof, headers for the water tubes, each having a wall provided with openings 35 of a diameter substantially equal to that of the water tubes, plugs for closing the openings in the headers, each plug having an opening through which the end of an air tube extends, and air collecting chambers communicating with the air tubes.

40 16. Heat exchange apparatus comprising a plurality of rows of double heat exchange elements, each consisting of an external water tube and an internal air tube, the air tubes projecting beyond the ends of the water 45 tubes, a pair of headers for each row of water tubes, each header having at its outer wall openings opposed to the water tubes and of a diameter at least as great as that of the water tubes, plugs for closing the openings 50 in the headers and having openings to receive the ends of the air tubes, the water tubes being expanded into the headers and the air tubes being expanded into the plugs, and collecting chambers for the air tubes to 55 divide each set thereof into a plurality of banks, each bank comprising several rows of tubes through which the air flows in parallel.

17. Heat exchange apparatus comprising a 60 set of air tubes and a set of water tubes, a flue for hot gases, the separate tubes of one set being contained within the separate tubes of the other set, a collecting chamber for tubes of one set, and flanged detachably return bends located in all of the chambers and 65 connecting tubes of the other set.

18. Heat exchange apparatus comprising a set of air tubes and a set of water tubes, a flue for hot gases, the separate tubes of one set being contained within the separate tubes of the other set, a collecting chamber for tubes of one set, headers and return bends located in the collecting chamber and connecting tubes of the other set.

19. Heat exchange apparatus comprising a set of air tubes and a set of water tubes, the separate tubes of one set being contained within the separate tubes of the other set, and collecting chambers for each set arranged at the ends of the tubes to provide for parallel flow of fluid through a number of tubes of each set, the collecting chambers of the one set being contained within the collecting chambers of the other set, and means for serially connecting the so contained collecting chambers to provide for series flow 85 of fluid therebetween.

In witness whereof I have signed my name to this specification.

ERNEST B. FREEMAN.
